UNITED STATES PATENT OFFICE

MARTIN THUM, OF ROCHESTER, NEW YORK

BED AND A SPRING BOTTOM

Application filed February 26, 1931. Serial No. 518,454.

The present invention relates to beds and to a spring bottom and an object of the invention is to provide a spring bed bottom which may be connected to the head member and the foot member of a bed without using side rails or pieces. Another object of the invention is to provide a spring bottom which is so constructed that it cannot cant or twist. Still another object of the invention is to provide a frame construction which does not become twisted or distorted due to the spring tension thereon.

To these and other ends, the invention consists of certain parts and combinations of parts all of which will be hereinafter described: the novel features being pointed out in the appended claim.

In the drawings:

Fig. 1 is a perspective view of the bed showing the springs removed from the spring bottom;

Fig. 2 is a perspective view of the foot piece of the bed;

Fig. 3 is an enlarged horizontal section showing the manner in which the spring bottom connects with the head and the foot piece;

Fig. 4 is a perspective view of the bed bottom with part of the covering broken away;

Fig. 5 is a horizontal section through the bed showing a portion of the covering of the bed bottom broken away;

Fig. 6 is an enlarged fragmentary longitudinal section; and

Fig. 7 is a fragmentary section on the line 7—7, Fig. 6, with part of the covering broken away.

In the illustrated embodiment of the invention, the spring bed bottom has two parallel sides each formed by a wooden board 1 with its wide sides upright and a horizontal board 2, the outer edge of which is flush with the outer face of the board 1, said board 2 projecting inwardly beyond the inner face of the board 1 so that its upper face forms a ledge on the inner side of the board 1. In other words, the planes of the two boards are at right angles to each other. The boards are secured together at their abutting portions by

glue and/or fastening means of any type. The ends of the frame of the bed bottom are formed by wooden boards 3, the opposite ends of which are received in grooves 4 in the boards 1 of the two sides of the frame while the lower edges of the boards 3 are received in grooves 5 in the upper faces of the boards 2. The boards 3 are spaced from the adjacent ends of the sides of the frame so that the sides project beyond the ends.

In order to brace the ends and the corners of the frame against inward movement, bracing means is interposed between the ends and the sides of the bed bottom frame. In this instance, the bracing of each end is effected by a wooden brace board 6 which is positioned at an incline between the inner face of the end board 3 and the upper side of the board 2, that end of the board 6 engaging the board 3 being bevelled at 7 and fastened to the board 3 by glue and/or fastening devices, and the board 2 having its upper faces notched at 8 to receive a corner of the board 6, the corner being glued and/or fastened to the piece 2, and the ends of the piece 6 being glued and/or fastened to the pieces 1.

The spring bottom, in this instance, is formed by a plurality of parallel inelastic straps or bands 9 rigidly secured by fasteners 10 to the foot end piece 3 of the bottom frame and extending substantially to the head end piece 3 to which each has, in this instance, an individual elastic connection formed by a coil 11 and a short metallic strap 12 which is by a fastener 13 secured to the outer face of the head end piece 3.

With the end in view of causing pressure on one strap to be distributed to adjacent straps, a covering of novel construction is provided for the straps of the bed bottom. This covering comprises an upper layer 14 secured at opposite ends to the end pieces 3 and extending loosely and entirely over the straps and their elastic connections but being loose over said elastic connections, and also free from the sides of the bottom member. A lower cover layer 15 extends between the foot end piece 3 to the springs 11, free from the sides of the bottom member, and is by parallel rows of stitches 16 secured to the 100

upper layer 14. It will thus be seen that the under sides of the springs 11 are exposed and do not contact with the under layer. In order to provide a cushion or head piece on the bed bottom over the springs 11, a stuffing 17 is arranged between the top cover and a head piece 18 has its forward edge secured to the cover by stitches 19 adjacent the ends of the stitches 16 and its rear edge secured to the head end piece 3 in a loose manner. A cover 20 may be provided for each side piece comprising a sheet of textile material preferably of the same material as the spring bottom cover 14 and 15. Each cover 20 may be secured at 21 to the under side of each piece 2 and at 22 to the inner face of each piece 1.

This spring bed bottom member has such strength that it may be used to connect directly with the foot and the head piece of a bed and take the place of the usual side rails. To this end, the posts 23 of the head and the foot head pieces 24 and 25 are provided on their inner faces with angle pieces 26 serving as hooks, and adjacent each corner of the bed bottom member are provided eyes 27. The extreme ends of the side pieces 1 abut the inner faces of the posts 23 on the outer sides of the hooks 26 and the eyes are situated between the outer face of the adjacent end piece 3 and the adjacent end of the side piece 1. The end of the side pieces 2 abut the posts below the hooks. The foot end piece and the head end piece are lower than the side 1, so that a mattress may be supported on the bed bottom between the side pieces 1 without danger of shifting sidewise.

What I claim as my invention and desire to secure by Letters Patent is:

A spring bed bottom member comprising a frame, including end pieces, inelastic straps rigidly secured to the foot end piece of the frame, and elastic connections between the head end piece and the straps situated adjacent the head end piece, and a cover having an upper layer secured to both end pieces and also having a lower layer extending from the foot end piece to a point on the inner side of the elastic connections exposing the under side of the elastic connections, the two layers being stitched together between the straps.

MARTIN THUM.
